UNITED STATES PATENT OFFICE.

WILLIAM HUFF, OF LANDESS, INDIANA, ASSIGNOR OF ONE-HALF TO CHARLES C. HUFF, OF SAME PLACE.

WASHING-MACHINE.

SPECIFICATION forming part of Letters Patent No. 462,946, dated November 10, 1891.

Application filed May 16, 1891. Serial No. 392,987. (No model.)

To all whom it may concern:

Be it known that I, WILLIAM HUFF, a citizen of the United States, and a resident of Landess, in the county of Grant and State of Indiana, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved double-acting washing-machine. Fig. 2 is a longitudinal sectional view of the same on a vertical plane through the middle. Fig. 3 is a transverse vertical sectional view on line $x-x$ in Fig. 2, and Fig. 4 is a perspective view of the inside rubber removed from the machine.

Like letters of reference denote corresponding parts in all the figures.

This invention relates to washing-machines of the type known technically as "reciprocating" rubbers; and it consists in the improved construction and combination of parts of a double-acting machine of that class, as will be hereinafter more fully described and claimed.

Referring to the accompanying drawings, the letter A designates the suds-box, which has a smooth concave bottom B, made, preferably, of zinc or galvanized sheet-iron and straight parallel sides C C. The latter are bored through on opposite sides for the insertion of the movable trunnion-pins D D, upon which the two rubbers swing. The larger or outside one of these consists of the straight side pieces E E and convex bottom F, made of parallel slats with narrow openings between them, the sides having slanting handles G G connected at their upper ends by the cross-piece H. The smaller inside rubber is constructed in substantially the same manner, consisting of the parallel sides E' E', convex slat bottom F', and inclined handles G' G', connected by the cross-piece H'; but the handles are set or inclined in a direction opposite to the handles G G of the outside rubber, though at the same angle.

To place the outside rubber in the suds-

box A it is necessary to first move a pair of turn-buttons I I, which are pivoted on the outside of the suds-box, to one side, so as to uncover from the outside the apertures 55 through which the pins or bearings D D are inserted. These may then be pushed out from the inside, so as to be withdrawn from the holes in the sides of the outer rubber, when this can be easily lifted out of the 60 suds-box. The inside smaller rubber is hung upon the inwardly-projecting ends of the trunnion-pins D D by means of vertical recesses or grooves K, cut into the sides E' E' on the outside and extending from the bottom F' radially up to the point f, forming the center, in the circle of which the convex bottom of the rubber forms the segment. This construction permits the inside rubber to be lifted out of the machine and replaced 65 without disturbing the movable trunnion-pins D D, which require to be pushed out only when it is desired to remove the larger outside rubber. When the machine is in use, these pins are prevented from coming out by 70 the turn-buttons I, as shown in Fig. 3. It will be observed that both the inner and outer rubbers are hung upon a common center—viz., the inwardly-projecting ends of the trunnion pins or bearings D D—and by the 75 arrangement of the inclined handles of the respective rubbers these will, when the rubbers are placed in the suds-box in their proper working position, project therefrom at approximately right angles to each other, with angles of about forty-five degrees between them and the top of the suds-box. This position of the handles makes it easy for the operator standing at one end of the machine to simultaneously work both handles in opposite directions, using the right hand for one and the left hand for the other; or, if desired, the machine may be worked by two persons, one standing at each end and each manipulating 80 one of the rubbers. Again, if it should be desired to operate the machine as an ordinary single-acting rubber, the outside or bottom rubber may be fastened to the suds-box by inserting a pin L through a small hole l in one of the sides C near the top of the suds-box and 85 into a registering hole m in the adjacent side E of the outside rubber, thus holding the latter 90 in place. The handles G G and G' G' are 95 inclined at an angle of about forty-five degrees to the horizontal, and the top of the suds-box is 100 inclined at an angle of about forty-five degrees to the horizontal.

stationary, while the inside rubber may be reciprocated in the usual manner.

To use the machine, whether used as a single or double acting rubber, the batch of clothes to be washed is placed in the concave receptacle formed by the outside rubber, the inner rubber having first been lifted off of its bearings D D. The inside rubber is then replaced, and the rubbers are manipulated by one or two operators, as above described, thus subjecting the clothes to a thorough rubbing on both sides. As there is no pressure or friction whatever against the bottom B, this can be made very thin, so as to reduce the weight of the machine, and as this bottom is perfectly smooth on the inside there are no nooks, corners, or other recesses where water can collect and rust the bottom after the suds have once been drawn off through the usual plugged hole in one side of the suds-box after washing.

Having thus described my invention, I claim and desire to secure by Letters Patent of the United States—

The combination, in a reciprocating-rubber washing-machine, of the suds-box having a smooth bottom and provided with the outside turn-buttons I, sliding trunnion-pins D, outside rubber having inclined handles and side apertures for the insertion of the inner ends of the movable trunnion-pins, and inside rubber having vertical recesses or grooves in the sides, whereby it may be suspended upon the projecting inner ends of the movable trunnion-pins and provided with handles inclined in an opposite direction but at a corresponding angle to the slanting handles of the outside rubber, substantially as and for the purpose herein shown and set forth.

In testimony that I claim the foregoing as my own I have hereunto affixed my signature in presence of two witnesses.

WILLIAM HUFF.
